UNITED STATES PATENT OFFICE

HENRY LIFSHUTZ, OF BROOKLYN, NEW YORK

SHOE

Application filed June 24, 1930. Serial No. 463,525.

This invention relates to shoes and more particularly to improvements in the sole construction and the manner in which margins of the upper are secured about margins of the sole.

One object of the invention is to provide a shoe having its sole so constructed that marginal portions of the upper may be very firmly attached to the sole and all danger of stitching employed therein from becoming worn and portions of the upper released eliminated.

Another object of the invention is to so form marginal portions of the sole that marginal portions of the upper may be tucked into the sole where they will be firmly secured by stitching and produce a shoe which will be very neat in appearance.

Another object of the invention is to provide a sole so cut about its margin that sewing of the upper to the sole may be accomplished without turning the shoe and to further so form the sole that a portion thereof will constitute a flap extending along the shank and against the front or breast face of the heel and thereby eliminate any break or dividing line between the shank and heel when the shoe is finished.

Another object of the invention is to so form the sole that the stitches may be firmly engaged with the sole without protruding from the inner or outer face thereof and eliminate roughness which might cause the shoe to be uncomfortable when worn.

Another object of the invention is to provide a shoe sole formed from a single piece of leather and which will be very simple in its construction and to which the upper may be very easily and quickly attached.

40 The invention illustrated in the accompanying drawings wherein:

Figure 1 is a longitudinal sectional view through the improved sole;

45 Figure 2 is a view taken along the line 2-2 of Figure 1;

Figure 3 is a perspective view of the improved sole, a portion thereof being shown in section and a flap forming part of the sole being turned upwardly to expose the portion 50 of the sole beneath the same;

Figure 4 is a transverse sectional view through the sole taken along the line 4-4 of Figure 3;

Figure 5 is a longitudinal sectional view through a shoe having the improved sole applied thereto;

Figure 6 is a transverse sectional view through the shoe taken along the line 6-6 of Figure 5;

Figure 7 is an enlarged view of approximately one-half of Figure 6, and illustrating the manner in which the upper is sewed to the sole; and

Figure 8 is a perspective view looking at the bottom of a portion of the shoe with the bordering strip turned back to show the manner in which the stitches engage marginal portions of the upper.

The improved sole constituting the subject matter of this invention has been shown applied to a low quarter shoe such as a pump or slipper but it is to be understood that it could be applied to a high shoe or any other type of shoe. This shoe which is indicated in general by the numeral 1 has the usual outer skin or leather 2, a lining 3, box 4, and counter 5. Marginal portions of the upper are secured about margins of the sole after which the heel 6 and shank or stiffener 7 are secured in place and an inner sole 8 glued in covering relation to the upper face of the main sole. The main sole indicated in general by the numeral 9 consists of a blank cut from leather and having the general shape of a shoe sole as shown in Figures 2 and 3. The blank from which the sole is formed will, of course, be cut in accordance with the type of shoe to which it is to be applied. From its heel end the sole is split longitudinally to form a tongue or flap 10 which is attached at approximately the junction of the shank and ball of the sole as shown clearly in Figure 5 and from the forward or attached end of this tongue the leather blank is split about its margin to form a marginal strip 11 having its rear ends meshing into the tongue or flap 10. The central portion 12 of the ball portion of the sole remains solid as it is uncut and constitutes a good anchorage for the bor-

dering strip 11 and forward end of the flap or tongue 10. After the flap and bordering strip have been formed margins of the blank are reduced in thickness from the under surface of its upper portion to form a pocket 13 about its margin and the blank is then slit on an angle along the line 14 parallel to its margin. It should be noted that when the blank is slit along the line 14 the point of 10 the knife extends towards the margin of the blank thereby forming a flap 15 extending entirely about the blank beneath the strip 11 and tongue 10 with its free edge facing inwardly.

15 While the drawing discloses the sole 9 split inwardly from its edges so that the upper strip or portion thereof is of greater thickness than the lower strip or portion of same, it will be understood that this is merely 20 a matter of illustration and that said sole may be split so that the outer strip or portion thereof is of the same or greater thickness than the inner strip or portion of the sole. This is merely a matter of degree and 25 is open to the choice of the manufacturer, according to the type of shoe that is being manufactured.

After the blank or sole has been cut as 30 shown clearly in Figures 1 and 3, it is ready to be applied to the upper. In doing so a last is fitted into the upper and the sole then set in place and temporarily tacked or otherwise secured to the upper. The tongue 10 and the strip 11 are turned back out of the 35 way after which marginal portions of the upper are folded inwardly to overlie marginal portions of the sole and fit within the pocket or seat 13, as shown at 16 in Figure 8. The marginal portions of the sole against which 40 the upper fit may be paired off and rounded transversely as shown in Figures 6 and 7 in order to provide a smooth surface and thereby prevent a line from appearing through the upper above the sole.

45 After the marginal portions of the upper have been fitted into the seat 13 of the sole the flap 15 is turned outwardly and stitches 17 are passed through the upper and the attached portion of this flap thereby very firmly securing the marginal portions of the 50 upper to the sole. The flap is then returned to its initial position where it may be glued if so desired and the bordering strip 11 thrust downwardly and glued from its inner 55 edge to the inner edge of the seat 13. The outer marginal portion of this bordering strip may be left free as shown in Figures 6 and 7 so that it projects outwardly a short distance from the upper or it may be glued 60 against the inturned marginal portion of the upper as shown in Figure 5. After the reinforcement 18 has been applied to the shank of the sole the heel 6 is set in place where it is firmly secured by a screw 19 and a suitable number of nails 20 and the tongue

10 then firmly glued against the shank with its rear end portion extending to cover the front or breast face of the heel where it is firmly secured by glue. The extreme end of the tongue is turned under the heel as shown 70 at 21 and the lift 22 then applied to the heel where it is secured by a suitable number of nails 23. The usual shank or stiffener 7 is applied as shown in Figure 5 and the insole 75 set in place where it is glued or otherwise firmly secured. By inspection of Figures 5, 6 and 7 it will be seen that a sole and upper 80 constructed and applied to each other in accordance with this invention will be very strongly united and since the stitches are 85 covered by a bordering strip which is relatively thick there will be no danger of the covering for the stitches becoming detached and exposing the stitches for engagement with the ground and resulting likelihood 90 of the stitches becoming worn. It will be further noted that by this arrangement the stitches may be applied without turning the shoe thereby permitting the sole and upper to be very easily and quickly applied to each 95 other. This materially reduces the time and cost of manufacture.

From the foregoing description of the construction of my improved apparatus, it will be seen that I have provided a simple, inexpensive and efficient means for carrying out the objects of my invention and while I have particularly described the elements best adapted to perform the functions set forth it is obvious that various changes in form, 100 proportion and in the minor details of construction may be resorted to without departing from the spirit or sacrificing any of the principles of the invention.

Having thus described the invention what 105 I claim is:

1. In a shoe, an upper, a sole, the sole being split and cut about its margin to form an inset shoulder, a channel and a covering strip, said upper having its marginal portion turned inwardly and fitted against said shoulder and secured by stitches passing through the upper and into the channel, the covering strip being secured in overlapping relation to the marginal flap and marginal portion of the 115 upper.

2. A shoe comprising a sole and an upper, the upper having its marginal portion fitted into a seat extending about the margin of the sole and covered by a shield formed integral 120 with the sole, the said sole having a channel formed therein and extending toward the adjacent sole edge, and stitches passing through the channel and marginal portion of the upper to firmly hold the upper in place 125 with the channel and stitches covered by said shield.

3. A shoe comprising a sole and an upper, the upper having its marginal portion fitted into a pocket formed about the margin of the 130

sole, the sole being formed with a stitch receiving channel about its margin inwardly from the edge of the upper and stitches being passed through the channel and upper to 5 firmly retain the upper in the pocket of the sole, said sole being formed with a covering for the channel, stitches, and marginal portion of the upper, and firmly secured in covering relation to the flap and marginal portion 10 of the upper after the upper has been stitched.

4. A shoe comprising an upper and a sole, said sole being split longitudinally from its heel end for a portion of its length to form a 15 tongue and between the forward end of the tongue and toe being slit about its margin to form a covering strip merging at its rear end into the recess formed by splitting the tongue from the sole, a marginal portion of the sole 20 being removed to form a seat to receive the marginal portion of the upper, and the sole being channeled in spaced parallel relation to its margin inwardly from said seat to form a circumferentially extending flap having its 25 free edge disposed inwardly, stitches passing through the attached side portion of the flap and the marginal portion of the upper to secure the upper in its seat, a heel applied to the rear portion of the sole with portions of 30 the heel overlapping the marginal portion of the upper and the stitches securing the same, the covering strip being firmly secured in place in overlying and covering relation to portions of the flap and the marginal portion 35 of the upper along the shank and ball of the sole, and said tongue having its rear portion secured in covering relation to the breast of the heel.

5. A shoe comprising an upper, a sole, said 40 sole being formed with a flap about its margin having its free side edges disposed inwardly from the margin of the sole, a shield formed integral with said sole, the marginal portion of the upper being disposed against 5 the sole about margins thereof, stitches passing through the marginal portion of the upper and through the attached side portion of 10 said flap, and said shield being secured in covering relation to the flap and stitches and 15 the marginal portion of the upper.

6. In a shoe, an upper, a sole therefor, said sole being split inwardly from its marginal edges to provide an underlying strip, said sole above said strip being formed with a 65 marginal shoulder and also provided with an inclined channel forming an adjoining inwardly directed flap, the marginal portion of the upper being adapted to be secured in said shoulder by stitching through said channel 70 and the strip being adapted to be secured, without stitching, to the marginal portion of said upper to cover the stitching of the latter.

7. The method of making a shoe consisting in applying an upper to a last without 65 securing means, applying a sole to said last,

said sole being split inwardly from its marginal edges to form an underlying strip, said sole being also provided with a marginal shoulder and formed with a channel directed toward said shoulder, applying the marginal edges of the upper to the shoulder of said sole, stitching the same thereto through the channel, and securing the strip, without stitching, to the marginal portion of said upper to cover the stitching of the latter. 75

8. The method of forming a shoe, consisting in stretching an upper over a last, applying a sole to said last, said sole being split transversely from its marginal edge to form an underlying strip, the upper wall of the split portion of the sole above the strip being formed with a marginal offset and formed with a channel directed towards said offset, drawing the marginal edge of said upper and temporarily securing the same in the marginal offset portion of said sole, stitching the marginal edge of the upper to the offset through said channel, removing the temporary securing means for the upper and securing, without stitching, said strip to the marginal portion of said upper to cover the stitching thereof. 80

9. In a shoe structure, a sole of a single piece of material split at the edges thereof for allowing the insertion of a shoe upper into the interior of said sole, an upper inserted into said split, and concealed stitching arranged between the opposed faces of the sole and substantially parallel to said faces and securing said upper to the inner split portion 95 of the sole only. 100

10. In a shoe structure, a single sole constituting both the inner sole and the outer sole of the shoe, an upper, and stitching in the interior of the sole securing the upper to said sole with the terminal edge portion of the upper in the interior of said sole, said stitching being concealed and arranged between the faces of the sole and substantially parallel thereto. 110

11. In a shoe structure, a sole constituting the inner and outer sole of the shoe, and an upper secured to said sole intermediate the inner and outer faces of the sole, by stitching entirely enclosed within the sole, said stitching being concealed and arranged between and substantially parallel to the faces of the sole. 115

12. In a shoe structure, a single sole forming the finished bottom of the shoe, a pair of edge flaps integral with said sole and split from the edge thereof, and having their free edges nearest the edge of the sole, an upper passed over and outside of the free edge of one of the flaps and having its edge portion covered by said flaps, and concealed means for securing the upper to the inner edge flap only. 120

13. In a shoe structure, a sole, a pair of edge flaps formed by splitting the edge of 130

said sole, and an upper secured to said sole by substantially horizontal concealed stitching between said flaps.

14. In a shoe structure, a sole forming both the inner sole and the outer sole of the shoe, a pair of edge flaps on said sole formed by splitting the sole along the edge thereof, a channel on the inner flap, an upper, stitching passing through said channel and said upper for securing the upper to the sole, and means for securing the outer flap to the inner flap and to the upper.

15. In a shoe structure, a sole of a single piece of material forming the inner sole and the outer sole of the shoe, and split along its edge to form an inner and an outer flap, said inner flap having an edge channel, and having an inclined seaming channel spaced from said edge channel, an upper arranged in said edge channel, stitching passing through said upper and through said inclined channel for securing the upper to the inner flap, and cementitious means for securing the outer flap to the inner flap and to the upper.

16. In a shoe structure, a sole of a single piece of material split at its edge to provide an outer lip having an unmutilated outer edge and an inner portion, an upper arranged with its terminal edge passing about the peripheral edge of the inner portion and extending away from said edge toward the center of the sole, and covered by said outer lip, means concealed in the interior of the sole for securing the edge of the upper to said sole, and means for securing said lip and inner portion together with the edge of the upper therebetween.

17. In a shoe structure, adapted to be made by a single lasting operation, a sole split at the edges thereof, an upper, and stitching concealed by the sole securing the upper in place in the split with its terminal edge in the interior of the sole, said stitching being interposed between the faces of the sole and arranged substantially parallel to said faces.

18. In a shoe structure, a sole of a single piece of material split from the heel to the break and further split along its edge to form an outer flap about the fore part of the sole and an inner flap below said outer flap, said inner flap having an edge channel for the reception of the edge of an upper and having a second channel spaced from said first channel and substantially parallel thereto, said channels extending about the entire sole inclusive of the inner edge flap, the sole having an unmutilated edge on the outer flap, an upper arranged with its terminal edge portion in the edge channel of the inner flap, stitching passing through the channels of the inner flap and through the terminal edge of the upper for securing the upper in place, a heel on the rear portion of the rear inner flap, and cement securing the inner and outer flaps on the forepart of the sole together, and securing

the rear outer flap to the front face of the heel.

19. The method of making a shoe, consisting of splitting a sole along the fore part of the edge thereof, positioning said sole on a last with the grain side out, arranging an upper about the last with the right side out, stitching the terminal edge of the upper to the inner split portion of the sole only, and cementing said sole together at the split thereof.

75
20. The method of making a shoe, consisting of partly splitting a sole by a cut directed from the edge of the sole toward its center, and securing the upper to the sole between the inner and outer faces of said sole by stitching concealed in the interior of the sole and arranged substantially parallel to the faces of the sole.

80
21. The method of making a shoe, consisting of partly splitting a sole, channelling one of the flaps formed by so splitting the sole and securing the edge of an upper to the channelled flap, and cementing the other flap on to the channelled flap and to the edge of the upper.

85
22. The method of making a shoe, consisting of partly splitting a sole to form two flaps, channelling one of the flaps on the face adjacent to the other flap, and securing the terminal edge of an upper to the channelled flap.

90
23. The method of making a shoe, consisting of partly splitting a sole, channelling one of the edge flaps of said sole on the face adjacent to the other flap, lasting said sole with the grain face uppermost, lasting an upper with the right side out, securing the upper to the channelled flap, and cementing the flaps together, whereby the edge of the upper becomes arranged in the interior of the sole.

95
24. In a shoe structure, a sole, edge flaps formed by splitting the edge of said sole toward the center thereof, and an upper passed outside of the edge of one flap and secured to said sole by stitching arranged between said flaps, and concealed thereby.

100
105
25. The method of making a shoe, consisting of temporarily securing a split sole to a last with the grain side out, stitching an unturned upper in the split of the sole by substantially horizontal concealed stitching while the sole remains on the last, and completing the shoe while the relative positions of the secured upper and sole and the last remain substantially unchanged.

110
In testimony whereof I affix my signature.

HENRY LIFSHUTZ.
